SEAL FOR BUNG RINGS

John R. Proctor, Bayonne, N. J., assignor to Atlas
Steel Barrel Corporation, Bayonne, N. J., a
corporation of New Jersey

Application August 30, 1938, Serial No. 227,601

5 Claims. (Cl. 220—39)

This invention relates to sealing metal containers against unauthorized opening and has particular reference to a means for sealing the plugged bung flange of metal drums in such manner as to preclude undetected removal of the plug to permit access to the contents of the drum.

An object of the invention is to effectively seal the plug against undetected access by means of a simple, inexpensive seal-cap and to so construct and arrange the seal-cap and the bung flange to which the cap is secured that the latter may be rapidly positioned in the flange without need of laborious centering, and subsequently locked in place rapidly and with a minimum of effort on the part of the worker.

An important feature of the invention resides in the ease with which the seal-cap may be applied and the simplicity of the operation by which it is locked in place. In accordance with the present invention the seal-cap is simply dropped in a recess provided therefor in the outer surface of the bung flange. The cap is provided with a peripheral flange which may then be expanded or forced radially outwardly into an undercut portion or cleft extending around the periphery of this recess, thereby locking the cap in its seat.

Other important features of the invention reside in the particular construction and arrangement of parts whereby the above objects are attained, the simplicity and ruggedness of the mechanism for accomplishing the same, and the effectiveness of the joinder between seal-cap and flange.

Various other objects and meritorious features of the invention will be apparent from the following description taken in conjunction with the drawings, wherein like numerals refer to like parts throughout the several figures, and wherein:

Figure 1 is an elevation of one form of tool adapted to perform one step of the method disclosed herein;

Fig. 2 is a fragmentary elevation, partly in section, illustrating the position of this tool after expanding the seal-cap into locking engagement with the bung flange;

Fig. 3 is a section along 3—3 of Fig. 2;

Fig. 4 is a section illustrating the initial step in operatively positioning the seal-cap in the bung flange;

Fig. 5 is a section similar to Fig. 4 with the seal-cap expanded into locking engagement with the bung flange;

Fig. 6 is a fragmentary elevation of a somewhat modified form of tool;

Fig. 7 is a section along 7—7 of Fig. 6;

Fig. 8 is an elevation, partially in section, of a modified form of seal-cap prior to expansion into locking engagement;

Fig. 9 is a similar view showing the form assumed by this modification after using the tool illustrated in Fig. 6, and

Fig. 10 illustrates in section a detail of the tool.

Referring now to Fig. 2 of the drawings, the reference numeral 10 represents the metal stock of a drum provided with an aperture adapted to receive a bung assembly. A bung ring having a flange 12 and internally threaded to receive plug 14 is positioned within the aperture in any suitable manner. As here shown the shank of the bung is extruded or expanded radially outwardly as indicated at 14 to grip the metal of the barrel stock immediately surrounding the aperture, together with backing ring 16, firmly between the extruded portion and the flange. Rotation of the bung ring within the aperture may be prevented by any suitable means, here shown in the form of biting surfaces 18 around the exterior of the bung ring shank immediately below the flange which are expanded into biting engagement with the side wall of the aperture and with the side wall of the backing ring 16.

The upper surface of flange 12 is provided with a recess 20 having an undercut or cleft 22 extending around its periphery. While the angle of undercut is not of paramount importance, I have determined that 45° is satisfactory.

One form of seal-cap suitable for my improved method of application, and adapted for use with the tool illustrated in Figs. 1—3, is indicated by the numeral 24. It comprises a crown portion 26 preferably rounded as indicated at 28 into a vertical side wall 30 and having an annular flange 32 with an angle piece 34 extending around the outer periphery thereof. The cap may be sheet metal and stamped in a single piece.

Plug 14 having been threaded into the bung ring, seal-cap 24 is dropped into the seat formed in the upper surface of the bung flange by recess 20. The seal-cap is so dimensioned that in performing this operation the outer periphery thereof just clears the upper tip of the 45° undercut indicated at 22. It is therefore apparent that the cap may be applied rapidly and easily, there being no need for centering or ad-

justing the same with reference to the bung assembly prior to locking the cap to the flange.

The angle piece 34 is then expanded radially outwardly into the undercut 22 of recess 20, thereby firmly locking the cap in the flange and precluding access to the drum by removal of the concealed plug without first removing the seal-cap. Such removal would be readily detected and thus the consignee of the drum contents would realize that the drum had been tampered with.

One form of tool for expanding this type of seal-cap into locking engagement with the bung flange is illustrated in Figs. 1-3. This tool comprises a housing 36 open at the base and having a skirt 38 externally threaded around the lower portion thereof to receive an internally threaded collar 40 which is provided with a lip 42 extending radially inwardly beyond the skirt 38. Four segmental expanding members 44 are positioned within the housing for radial movement therein. An endless coil spring 46 positioned within alined grooves 48 in the outer walls of the expanding members tends constantly to contract them.

The inside face of each expanding member is tapered along spaced portions as indicated at 50 and 52, thereby forming in the aggregate an upper cone and a somewhat smaller lower cone for a purpose to be more clearly brought out hereinafter. Contraction of the expanding members 44 is limited to such movement as will bring the vertical faces 54 of the inside bottom wall portions of each segment into contact with one another. This movement is not sufficient to permit the said expanding members to drop through the supporting lip 42 which retains them in the housing.

A casing sleeve 56 is threaded into an annular groove 58 in the top of casing 36 and an apertured cap 60 is threaded as indicated at 62 onto the upper end of the said casing sleeve. Plunger 64 is slidable through the aperture in cap 60 and is provided with a reduced portion 66 adjacent its lower extremity adapted to slide through an opening in the top of housing 36. The shoulder 68 formed by the reduced lower portion of the plunger clears the top of casing 36 when the plunger is fully depressed. A slidale collar 70 is adjustably positioned with reference to plunger 64 as by means of set screw 72, which collar provides an upper seat for coil spring 74, the bottom of which seats on housing 36, thereby providing a constant force tending to urge the plunger to the upper limit of its movement. In the particular form illustrated the upper portion of the plunger is reduced in diameter to form a shoulder 76 which provides a stop for collar 78 slidably positioned on the upper reduced portion of the plunger and adjustable with reference thereto by means of set screw 80. A heavy cast iron ball 82 is slidale along the upper reduced portion of the plunger, its upper limit of movement being marked by collar 84 which is preferably slidale and adjustable with reference to the plunger.

The under side of housing 36 is provided with a recess 86 for seating the upper cylindrical portion 88 of a generally cone-shaped cam 90 integral with or secured to the bottom of the plunger, the taper of which corresponds to the taper of spaced cone seats 50 and 52 formed by the segmental expanding members. These cone seats are separated by a straight-walled portion 92 which forms a seat for the cylindrical wall portion 98 of the cam cone.

Each segmental expanding member 44 is provided with peripheral toe portions 94, the hypotenuse of each of which is somewhat rounded, as indicated in somewhat exaggerated form in Fig. 10 at 96, to facilitate the expanding action thereof in locking the seal-cap in the undercut of the bung flange.

In operation the seal-cap 24 is first dropped into recess 20 as indicated in Fig. 4. The weight 10 of ball 82 overcomes the normal upward thrust of spring 74 to retain cam cone 90 in its lower seat when the tool is not in use, thus forcing the expanding segments outwardly against the tension of coil spring 46 to prevent relative movement of the parts and consequent wear and tear. When seal-cap 24 is to be expanded into locking engagement, ball 82 is lifted to remove its weight and permit coil spring 74 acting on collar 70 to urge the plunger to its uppermost position, the limit of upward movement being reached when cam cone 90 seats in socket 86 provided therefor in casing 36. As cam cone 90 moves to its upper seat, spring 46 contracts the expanding members. When the tool is contracted the inside of toe portions 94 just clear the rounded crown 28 of the seal-cap, which is somewhat higher than angle portion 34 of the seal-cap flange. This rounded crown therefore functions as a guide to prevent the toes of the expanding segments from fouling the upper edge of angle piece 34 when the sealing tool is positioned. The toes 94 being seated on flange 32 of the seal-cap, the collar 78 is struck forcibly by sliding ball 82 downwardly. This forces the plunger downwardly and cam cone 90 operates against the tapered seat of lower cone 52 to expand the segments. During expansion the toes 94 force the upturned edge 34 of the seal-cap into the undercut 22 of the recess provided in the bung flange.

The tool is released by again lifting ball 82, thereby permitting the spring 74 to lift cam cone 90 into its upper seat which in turn permits spring 46 to contract the expanding segments.

The rounded hypotenuse 96 of toes 94 on the expanding segments tends to draw the vertical line of the seal-cap rim downwardly while the base flange 32 remains seated in the recess 20. The metal in seal-cap flange 32 and its rim or angle portion 34 is preferably sufficient to leave an inturned marginal rim portion 98 within the cleft provided by undercut 22, thus rendering unauthorized removal of the seal-cap still more difficult.

A somewhat modified form of seal-cap is illustrated in Figs. 8 and 9. Fig. 8 illustrates the structure prior to expansion into the flange recess. This form of cap is provided with an outwardly extending marginal skirt or flange 100 which is, like the previously described cap, self-centering in that its diameter is slightly smaller than the inside diameter of recess 20 in the bung flange, thereby permitting the cap to readily find its seat.

A tool such as that illustrated in Figs. 6 and 7 may be employed for expanding this form of cap, for which operation a square ring face 102 may be used. In the form illustrated this ring face is supported by a plurality of arms 104 integral with or connected to a handle 106 which is preferably weighted by a ball 108.

After dropping the cap in its seat, ring face 102, the diameter of which is slightly greater than the diameter of the upper cylindrical portion of the cap, is brought down over said upper portion into engagement with skirt portion 100.

Continued downward movement of the tool forces the said skirt radially outwardly into the undercut or cleft 22, thereby locking the seal-cap in the bung flange in the manner hitherto described. A slight difference is to be noted in that the annular skirt 100 is squared out into a peripheral flange 110 extending at right angles to the cylindrical upper portion of the cap and no inturned marginal rim portion such as that illustrated at 98 in Fig. 5 is obtained.

While other tools of even simpler construction than that illustrated in Figs. 6 and 7 may be used for locking-in the seal-cap illustrated in Fig. 8, the ring is desirable because its action conforms the wall metal of the seal-cap to any slight irregularities in the dimensioning or workmanship of the cleft 22. If the margin of flared skirt 100 seats in cleft 22 before the flare has been shifted to form substantially a right angle as illustrated in Fig. 9, continued movement of the ring along the wall of the seal-cap will so deform the metal as to shift the crease forming the angle inwardly, thereby increasing the height of said cylindrical wall portion and decreasing the width of the peripheral flange 110.

While in this application I have disclosed certain preferred means for locking the seal-cap in the bung flange cleft, it will be apparent that various other mechanisms may be used to accomplish this. Likewise, certain preferred forms of seal-cap have been illustrated herein without intending to limit in any way the improved method disclosed herein which consists fundamentally in providing a cleft or undercut extending around the periphery of a recess in the bung flange, seating in said recess a cap having an expansible peripheral flange, and expanding or forcing said flange into the cleft.

Various modifications of the structures and

means heretofore described will be apparent to those skilled in the art and for that reason I wish to limit myself only within the scope of the appended claims.

5. What I claim is:

1. A seal cap for closing the opening in a bung ring, said cap comprising a crown portion having an outwardly extending marginal flange around the base of the crown, said flange terminating in 10 an upwardly extending angle piece.

2. A seal cap for closing the opening in a bung ring, said cap comprising a crown portion having a marginal flange extending around the base of the crown, said flange being flared away from 15 the crown portion.

3. A seal for a bung ring having an outwardly disposed flange comprising, in combination, a recess in the outer face of said flange, an outwardly extending undercut or cleft extending 20 around the base periphery of the recess and opening thereto, and a seal cap including a crown portion and a marginal flange portion extending outwardly and into said cleft.

4. A seal for a bung ring having an opening 25 and an outwardly disposed flange comprising, in combination, a recess in the outer face of said flange, an outwardly extending undercut or cleft at oppositely disposed portions of the base periphery of the recess opening thereto, and a 30 seal cap for closing the opening in the ring, said seal cap including a crown portion and a marginal flange portion extending outwardly and into said cleft.

5. A bung ring having an opening therein and a flange at one end, said flange including an 35 annular recess in its upper face having an outwardly extending undercut or cleft extending around its base periphery.

JOHN R. PROCTOR.
